UNITED STATES PATENT OFFICE.

JAMES E. HARDY, JR., OF LOUISVILLE, KENTUCKY.

WHIFFLETREE.

1,409,713.

Specification of Letters Patent. Patented Mar. 14, 1922.

Application filed February 12, 1921. Serial No. 444,549.

To all whom it may concern:

Be it known that I, JAMES E. HARDY, Jr., a citizen of the United States, residing at Louisville, in the county of Jefferson and State of Kentucky, have invented certain new and useful Improvements in Whiffletrees, of which the following is a specification.

This invention relates to improvements in whiffletrees, it relating more particularly to the construction of the individual parts of such devices, such as single-trees, double-trees, treble-trees, evener-bars and the like, being also applicable to such devices as pole yokes, implement hitches, etc.

The object of the invention is to provide a structure which will be economical in manufacture and at the same time of great strength and durability.

A more specific object of the invention is to provide a structure of the character referred to which will embody a central metallic core or body reinforced by wooden side strips, together with the trace hooks, center loops or eyes, or other attaching devices, so arranged that the attaching devices are connected directly with the center metallic core to furnish a more secure fastening for such devices, and eliminate other disadvantages incident to connecting the devices to the wood.

In the accompanying drawings:

Fig. 1 is a top plan view of a whiffletree part, in this case a single-tree.

Fig. 2 is a side view of the same.

Fig. 3 is a longitudinal section on the line 3—3 of Fig. 1.

In the construction of devices of this character, it has been common to make them of wood and also of metal. When constructed of wood, the trees are liable to breakage and the attaching eyes and hooks become loose as the wood shrinks, and when constructed of metal they must be made light enough to compete with the wooden trees, as a result of which the trees bend easily and are then difficult to straighten. Some attempts have also been made to construct such devices of wood and metal, but all structures of this character with which the applicant is familiar have all of the disadvantages of the wooden trees in the manner of securing trace hooks and other attaching devices thereto, in that the devices are con-

nected to the wood and thereby become loose when the wood shrinks.

Referring to the drawings, 1 represents a strip or bar of metal, preferably steel, to the respective sides of which are secured, by rivets 4, strips or bars of wood, 2 and 3. The wooden bars are shorter than the metallic bar so as to leave the ends of the metallic bar exposed, as indicated at 1^a. To these extended ends 1^a of the metallic bar are pivotally attached, by rivets 6, the yoke-shaped parts 5^a of trace hooks 5. Attached to the center of the tree thus formed, by a rivet 8 which passes through the respective bars of wood and steel, is the yoke-shaped part 7^a of a loop or eye 7 by which the single-tree is attached to the double-tree of other part of the whiffletree.

By the construction described it will be seen that a tree is provided which is economical in manufacture and strong and durable in character, and also one in which the attaching hooks and eyes are secured in a manner to bring the strain of draft directly upon the steel core, the hooks being attached solely to this core in a way which will not only obviate the disadvantages incident to the shrinkage of the wood but also which will eliminate the use of the usual ferrules employed for the purpose or other more expensive manners of connection.

Having thus described my invention, I claim:

In a structure of the character described, a laminated tree consisting of a central metallic bar and wooden bars or strips above and below said central metallic bar, means for securing said bars together, the central metallic bar having end extensions that project beyond the laminated part of the structure, thereby forming an integral single supporting member extending from a point beyond one end of the structure to a point beyond the other end of the structure, and attaching devices so arranged that one device will be attached to each end extension and lie adjacent the end of the laminated structure.

In testimony whereof, I have hereunto set my hand this 7th day of February, 1921.

JAMES E. HARDY, JR.
